(57) **CLAIM**

We claim the ornamental design for a handheld pump, as shown and described.

DESCRIPTION

FIG. 1 is perspective view of the handheld pump of the present invention;

FIG. 2 is a front elevation view of the handheld pump of the present invention;

FIG. 3 is a rear elevation view of the handheld pump of the present invention;

FIG. 4 is a left side elevation view of the handheld pump of the present invention;

FIG. 5 is a right side elevation view of the handheld pump of the present invention;

FIG. 6 is a top plan view of the handheld pump of the present invention;

FIG. 7 is a bottom plan view of the handheld pump of the present invention; and,

FIG. 8 is a rear perspective view of the handheld pump of the present invention.
